UNITED STATES PATENT OFFICE

EDWARD A. SWEELY, OF ALEXANDRIA, VIRGINIA, AND NORMAN T. ANDERSON, OF WASHINGTON, DISTRICT OF COLUMBIA

CLOSURE FASTENER, SEAL PIN TYPE

Application filed April 3, 1931. Serial No. 527,586.

Our invention relates to what in the freight car art is commonly designated as seal pins, designed to fasten and lock two parts or members together, for instance, a door or cover to close an opening, and the pin sealed in its locked position by a metal sealing strip passed through the pin and held, say, by a lead seal, so that the pin can not be removed except by first breaking the seal, the pin serving to seal the parts in their interlocked relation. The purpose of the present invention is to so form the seal-pin that it will have a wider range of movement in a relatively small area, and possess a degree of flexibility that will avoid cramping in movement of the pin into locking and unlocking positions, and insuring the easy entrance of the pin into its keepers.

To the accomplishment of the foregoing and such other objects as may hereinafter appear the invention consists in the features hereinafter described and then sought to be clearly defined by the appended claims, reference being had to the accompanying drawing forming a part hereof, and in which,

Figure 1 is a perspective view of part of a car roof formed with a hatch-way opening and hinged cover for the same, and showing the seal-pin applied to lock the cover in a wholly or partially closed position;

Figure 2 is a perspective view of the seal-pin, detached.

In the drawing the numeral 1 designates part of a freight car provided with a hatch-way frame 2 applied to an opening in the car roof and through which material may be supplied to the interior of the car, for instance a refrigerant, such as ice if the car be a refrigerating car. The numeral 3 designates a door or cover attached by suitable hinges 4 to the car roof to wholly or partially close the hatch-way opening, and 5 designates a swinging link attached to the car roof and formed with a series of openings 6 adapted to receive the seal-pin in a selected opening to lock the cover in the position to which adjusted. The parts thus indicated may be of any desired, suitable construction. The improved seal-pin is designated by the numeral 7, and comprises a base-shank 8, preferably

formed with an off-set portion 9 and adapted to be attached to a suitable metal base plate 10 bolted or otherwise secured to the hatch-way cover by a pivot bolt passing through an opening 11 in the base-shank and into the base-plate 10 so that the base-shank may be rotated. To the base-shank 8, say to its off-set portion 9, an angular hook-shaped member 12 is swiveled, say by a pivot-pin 13, so that the hooked-shaped member may swing sideways relatively to the rotatable base-shank 8, thus giving to the seal-pin a wider range of movement in a comparatively small area, with a more or less degree of flexure, as the jointed seal-pin will have two independent centers of rotation, one being the pivot-bolt of the base-shank and the other the swivel or pivot 13 of the hook-shaped member on the base-shank of the seal-pin and which provides a flexible joint at the swivel points. The flexure thus provided for the seal pin tends to prevent cramping action between the seal pin and the cooperating locking link where the pin passes through the openings in the link and associated parts in movement of the seal pin into and out of locking position. In practice, the base-plate 10 is formed with spaced apart perforated ears 14 and 15 at opposite ends of the plate between which the cooperating link 5 may lie for locking the door in either a wholly closed or partially opened position. With the door wholly closed the link 5 will lie between the ears 15 and the seal pin will pass through the registering openings in those ears and in the link 5 and thus the cover to the hatch-way opening will be locked in its closed position. If the cover is to be locked in a partially opened position as illustrated in Figure 1 of the drawing, the link 5 will lie between the ears 14 and the seal pin passed through the registering openings of the ears 14 and the link 5 and the cover held in its partially opened position as under other constructions in use for the purpose. For convenience one of the seal-pins is attached to the base-plate 10 adjacent to one set of ears, and another to the plate adjacent to the other set as illustrated in Figure 1 of the drawing. The seal pin formed as illustrated and described is

strong and efficient in use and while its cost may be more than under other constructions the advantages gained off-set the extra cost.

5 The end of the angular member 12 of the seal-pin will be made with a slot 16 to receive a metal strip (not shown) to which a lead seal will be affixed in a well-known way to prevent withdrawal of the pin until the seal is broken.

10 We have illustrated and described the preferred details of the parts constituting the seal pin but changes may be made therein without departing from the scope of the invention as sought to be defined in the following claims. Nor is the seal pin confined in its use to the other cooperating elements selected for purposes of illustrating one embodiment of the invention as it may be used under other conditions and where the seal-pin may possess the functional features embodied in the seal-pin as herein described.

Having described our invention and set forth its merits what we claim is:—

15 1. A seal-pin comprising a pivotal shank member, and a second member pivotally mounted on the shank member and having its free end extending in a plane substantially at right angles to the axis of both pivots, each member being free to turn on its independent axis in movement of one member into position for engagement with a cooperative locking member.

20 2. A seal pin comprising a pivotal shank member having an off-set portion, and a second member pivotally mounted on the off-set portion of the shank member, one member having its free end extending in a plane substantially at right angles to the axis of both pivots, each member being free to turn on its independent axis in movement of the free end of one member into position for engagement with a cooperative locking member.

25 3. A fastener comprising perforated ears, a locking member formed with perforations to register with the perforations of the ears, and a seal-pin including a pivotal shank member, and a second member pivotally mounted on the shank member and positioned to enter registering openings in the ears and locking member, each member being free to turn on its independent axis in movement of the free end of one member into position for engagement with the locking member.

30 4. A fastener embodying a seal-pin comprising a pivotal shank member and a second member pivotally mounted on the shank member, the second member having a free end extending in a plane substantially at right angles to the axis of both members, and each being free to turn on its independent axis in movement of the free end of one member into position for engagement with a cooperative locking member, and means for securing the

pivotally mounted member in a projected locking position.

35 5. A fastener embodying a seal-pin comprising a pivotal shank-member and a second member pivotally mounted on the shank member, each member being free to turn on its independent axis in movement of the free end of one member into position for engagement with a cooperative locking member, and means for securing the pivotally mounted member in a projected locking position.

40 6. A fastener embodying a flexibly jointed two-part pivotally mounted seal-pin member, each part having an independent axis of rotation and means for securing the seal pin member in a locking position.

45 In testimony whereof we affix our signatures.

EDWARD A. SWEENEY.
NORMAN T. ANDERSON.
